UNITED STATES PATENT OFFICE.

VICTOR F. VROMAN, OF RACINE, WISCONSIN.

ELECTRIC CORN POPPER.

Application filed March 28, 1927. Serial No. 179,001.

This invention relates to an electric corn popper.

Objects of this invention are to provide a novel form of corn popper which is of extremely simple construction, which is efficient in operation, and which may be very cheaply produced and applied to corn poppers of the conventional type so that the article may be made as a unit and subsequently secured to the popper or else may be made as a unit with the popper itself and thus sold to the trade.

More specifically, objects of this invention are to provide a novel form of heater unit which may be stamped with its primary part formed from a single sheet of material in a simple type of blank, and which is so constructed that feet are formed integral with the blank and adapted to support the popper in a sliding manner upon any suitable support, the blank providing a shield for the heating element itself and such heating element being carried between the shield and the bottom mesh of the popper.

An embodiment of the invention is shown in the accompanying drawings in which:

Figure 1 is a view of the popper and unit attached;

Figure 2 is a sectional view showing the unit as it appears removed from the popper;

Figure 3 is a transverse sectional view on the line 3—3 of Figure 2;

Figure 4 is a sectional view on the line 4—4 of Figure 2;

Figure 5 is a view of the blank laid out flat.

Referring to the drawings, it will be seen that the device is formed from a main blank, as shown most clearly in Figure 5. This blank is stamped from sheet metal and comprises a main body portion 1 having projecting sides 2 equipped with attaching ears 3. Further, the blank is provided with outwardly projecting legs 4 and with a portion 5 adapted to be turned up and to receive the connecting terminal prongs 6, as shown in Figure 2. The legs 4, as shown in Figure 1, are bent downwardly and are then turned so as to provide a rounded bottom support adapted to freely slide over any smooth suitable surface.

The ears 3 are adapted to be riveted or otherwise secured directly to the sides of the pop corn popper 7, as shown in Figure 1, the side portions 2 being positioned in contact

with the sides of the popper for rigidity. 55 The connecting prongs are adapted to receive the usual plug or connector 8 of the electric cables 9, such cables extending outwardly and attached to the handle 10 and provided with the usual plug 11 adapted to be plugged 60 into an electric socket.

The heating unit is connected to the terminals 6 and comprises a plurality of strands 12 which are threaded through porcelain or other insulating washers or bushings 13 carried by transverse end members 14 and by an intermediate member 15. In the form shown, three of such supporting members are employed, although obviously any number may be used in order to securely hold 70 the heating strands or the heating element 10 in place.

It is to be noted particularly that the heating element is housed between the bottom of the wire mesh popper 7 and the main body 75 portion 1 of the blank or supporting plate. Thus, the heating unit is very securely guarded against contact with the hands of the operator or with any projecting part that may be found upon the support upon 80 which the popper is rested.

In using the device, the popper is filled with corn and the cover locked in the usual manner and thereafter the heating element is connected by plugging into a suitable electric socket. The popper is gently shaken in the usual manner by means of the handle 10 and the device slides back and forth as a unit and is carried by the legs 4 which slide upon a suitable support. 90

The pop corn is held out of contact with the heating element and the heating element is shielded on its underside so that the heat is thrown back into the body of the pop corn and a maximum efficiency is attained. 95

It will be seen that the device is of extremely simple construction and may be very cheaply manufactured and readily assembled. Further, by having the end members 14 set inwardly of the ends of the plate 100 1 the heating element is thoroughly protected even at its ends.

Although the invention has been described in considerable detail, such description is intended as illustrative rather than limiting 105 as the invention may be variously embodied and as the scope of such invention is to be determined as claimed.

I claim:

A heating unit for a pop corn popper comprising a blank formed from a single piece of sheet material and having attaching corner

5 ears turned upwardly therefrom and adapted to be attached to a pop corn popper, said blank having downwardly extending supporting legs terminating in rounded up-

turned bottom portions, said plate having up-turned integral side flanges, and a heating element located above said plate and between 10 said flanges.

In testimony that I claim the foregoing I have hereunto set my hand at Racine, in the county of Racine and State of Wisconsin.

VICTOR F. VROMAN.
